CABINET FOR ELECTRONIC EQUIPMENT

Wilson S. Geisler, Jr., Atherton, Calif.

Application September 3, 1957, Serial No. 47,587

Term of patent 3½ years

(Cl. D26—5)

Fig. 1 is a perspective view of a cabinet for electronic equipment, showing my new design;

Fig. 2 is a side elevational view, the opposite side being a substantial mirror image thereof; and

Fig. 3 is a front elevational view thereof.

I claim:

The ornamental design for a cabinet for electronic equipment, as shown and described.
